UNITED STATES PATENT OFFICE

157,614

WAFFLE IRON

Nicolas Milano, Euclid, Ohio

Application May 5, 1949, Serial No. 2,466

Term of patent 14 years

(Cl. D81—10)

To all whom it may concern:

Be it known that I, Nicolas Milano, a citizen of the United States, residing at Euclid, in the county of Cuyahoga and State of Ohio, have invented a new, original, and ornamental Design for Waffle Iron, of which the following is a specification, reference being had to the accompanying drawing, forming part thereof.

In the drawing:

Figure 1 is a top plan view of a waffle iron, showing my new design in closed position,

Figure 2 is a side elevation of the same,

Figure 3 is an end view of the same, and

Figure 4 is a perspective view of the waffle iron showing the complementary iron sections opened.

I claim:

The ornamental design for a waffle iron, as shown.

NICOLAS MILANO.
